UNITED STATES PATENT OFFICE.

JAMES HOWDEN HUME, OF GLASGOW, SCOTLAND, ASSIGNOR TO JAMES HOWDEN & COMPANY, LIMITED, OF GLASGOW, SCOTLAND.

FURNACE FRONT.

1,425,095.

Specification of Letters Patent. Patented Aug. 8, 1922.

Application filed December 4, 1919. Serial No. 342,337.

To all whom it may concern:

Be it known that I, JAMES HOWDEN HUME, a subject of the King of the United Kingdom of Great Britain and Ireland, and residing at 5 Glasgow, Scotland, have invented a certain new and useful Improvement in Furnace Fronts, of which the following is a specification.

This invention relates to improvements in 10 furnace fronts for forced draught installations more particularly to fronts fitted with side air valves as in installations of the Howden type.

The invention has been primarily designed 15 for furnaces adapted to operate with either solid or liquid fuel, it being understood, however, that the invention is also applicable to furnaces for use with solid fuel only.

It has already been proposed to provide in 20 such furnaces interconnected side air valves operatively connected to a device for locking the firing door contrived to insure that the door cannot be opened unless and until the side air valves are closed.

25 Certain constructions of furnace front do not lend themselves to the interconnection of the side air valves. There is also to be taken into consideration that furnace users to whom the employment of separately operat-

30 ed side air valves is familiar do not readily become accustomed to a construction having a single means for operating the side air valves.

The present invention provides a construction 35 having separately operable side air valves, each valve being operatively connected with means for locking the door so that the door cannot be opened unless and until both side air valves are closed.

40 In the accompanying drawings Fig. 1 is a front elevation, Fig. 2 a vertical section and Fig. 3 a fragmentary horizontal section of a furnace front embodying the invention. Fig. 4 is a view corresponding to Fig. 1 45 showing a modification.

Fig. 5 is a vertical section of the furnace front. Fig. 6 is a horizontal detail section showing the connection of the left handle with the left air valve; Fig. 6^a is a horizontal 50 detail section showing the connection of the right handle with the right air valve, and Fig. 7 is a fragmentary enlarged view of the door locking device shown in Fig. 1.

Similar reference numerals denote similar 55 parts in the several views.

Referring to Figs. 1 to 3, 1 denotes the firing door at the opposite sides of which are the handles 2 and 3 for operating the side air valves. Operatively connected with the left hand handle 2 is a locking bolt 4 60 slidable in a guide member 5. In the position illustrated in Fig. 1 the bolt 4 is clear of the door, the handle 2 being in the position corresponding to the closed position of the left hand side air valve. When the handle 2 65 is moved in clockwise direction to open the air valve, the bolt 4 is protruded and occupies a position in interfering relation with the firing door so that the door 1 cannot be opened so long as the left hand side air valve 70 is open. Connected to the handle 3 for the right hand side air valve is a rod 6 slidable in guides 7 and having an upward projection 8. In the position shown in Fig. 1 the projection 8 is clear of the door 1, the handle 75 3 being in the position corresponding to the closed position of the right hand side air valve. When the handle 3 is moved in counter-clockwise direction to open the right hand side air valve, the projection 8 is shifted to the right so that it comes into interfering relation with the firing door 1; that is, the door 1 cannot be opened so long as the right hand side air valve is open.

The handle 2 is connected with a shaft 9 85 on which is mounted a bevel gear wheel 10 meshing with a similar bevel gear 11 fixed to a shaft 12 which carries the left hand side air valve 13, so that when the handle 2 is moved clockwise to the position denoted 90 by broken lines in Fig. 7, the bolt 4 will be in position to lock the door 1 and the said valve will be opened; and when the said handle is in the position shown in Fig. 1 and in full lines in Fig. 7, the said valve will 95 be closed and the door 1 unlocked.

In a similar manner and by similar means the handle 3 is connected with the right hand side air valve 13^a, as will be understood from Fig. 6^a. 100

The construction shown in Fig. 4 is substantially similar to that of Fig. 1, the rod 6^a being, however, differently connected to the handle 3^a and being slidable in guide members 7^a, 7^a between which the slide rod 105 6^a has an upward projection 8^a shiftable into and out of interfering relation with a depending projection 1^a on the firing door.

I claim:

In combination with a furnace front for 110

forced draught installations, a firing door, two air valves, one at each side of said firing door, two operating handles, one for each valve, and two door locking members, one connected to each handle for preventing the opening of said firing door until both handles are in position to close both valves.

In testimony whereof I have signed my name to this specification in the presence of two subscribing witnesses.

10

JAMES HOWDEN HUME.

Witnesses:

KATE FOTHERINGHAM,
ISABEL ROLLO.
